UNITED STATES PATENT OFFICE.

DELLAMOIN L. HAMILTON, OF COLFAX, ILLINOIS.

COMBINED DOOR LOCK AND LATCH.

1,055,527.

Specification of Letters Patent. Patented Mar. 11, 1912.

Application filed February 8, 1912. Serial No. 675,363.

To all whom it may concern:

Be it known that I, DELLAMOIN L. HAMILTON, a citizen of the United States, residing at Colfax, in the county of McLean and State of Illinois, have invented certain new and useful Improvements in Combined Door Locks and Latches, of which the following is a specification, reference being had to the accompanying drawings.

10 My invention relates to new and useful improvements in the art of locks and latches and more particularly to a combined lock and latch and my object is to provide a device of this character which will effectively prevent persons having malicious intent, from opening doors.

A further object of the invention resides in providing a device which will permit of the door being opened upon the turning of the knob from the inside but which will not permit of the knob being turned from the outside and a further object resides in providing means which will require a door to be opened from the outside by means of a 25 key inserted through the knob.

A still further object resides in providing means whereby the door may be opened from the inside, even though a key, whether the proper or a fake one, is disposed in the outer knob and a still further object resides in providing a device which is extremely simple and durable in construction, inexpensive to manufacture, and one which will be very efficient and useful in operation.

35 With these and other objects in view, my invention consists in the novel features of construction, combination and arrangement of parts, as will be hereinafter referred to and more particularly pointed out in the 40 specification and claims.

In the accompanying drawings, forming a part of this application, Figure 1 is a fragmentary front elevation of a door showing my improved lock applied to use thereon; Fig. 2 is a side elevation of the door having my improved lock applied to use thereon; Fig. 3 is a fragmentary side elevation of the door frame showing the keeper applied thereto, which is adapted to receive 45 in engagement therein, the locking bolt; Fig. 4 is a vertical section as seen on line 4—4; Fig. 5 is a similar view, as seen on line 5—5; Fig. 2, and Fig. 6 is a top plan view of the locking bolt removed.

50 In carrying out my invention I shall refer to the drawings, in which similar reference

characters designate corresponding parts throughout the several views and in which I indicates a door of any preferred type, within which is disposed, from the free or swinging end thereof, a barrel or tubular member 2, the one end of said tubular member having the plate 3 formed thereon which is countersunk in the swinging end of the door and held in position by means of the screws 4. Slidably mounted in the barrel or cylindrical member 2 is a locking bolt or latch 5, which is circular in cross section and is designed to fit snugly within said barrel, said bolt 5 being bifurcated at its rear end and the bifurcations, or arms 6 and 7 thereof provided with alining longitudinal slots 8.

Extending transversely through the door 1 and through the alining slots 8 of the bifurcations 6 and 7 is the knob spindle 9, which is square in cross section and has mounted thereon, an arcuate trip member or the like 10, said trip member being disposed between the bifurcations 6 and 7 and the coil spring member 11, which is mounted in a central longitudinal channel 12 in the bolt 5, has one end of the same engaged with said member 10, while the opposite end thereof is engaged with the end wall of channel 12, whereby it will be seen that said bolt 5 is adapted to be normally disposed in its extended position, as shown particularly in Fig. 5.

Extending transversely through the bifurcations 6 and 7, immediately adjacent their rear ends, is a shaft or pin 13, upon which is pivotally mounted the ends of a pair of arms 14 and 15, said arms being disposed in opposite directions and connected intermediate of their ends, by means of a small coil spring 16. The free ends of these arms 14 and 15 are adapted to contact with a pair of shoulders 17 and 18 respectively, on the arcuate trip member 10, which will limit the outward movement of the sliding bolt 5 and it will be seen that as the spindle 9 is turned in either one direction or the other, the shoulder, contacting with one of the arms, will force the respective arm rearwardly, thereby causing the locking bolt 5 to be withdrawn. In this connection it must be stated also that the portion of the door frame 19, immediately adjacent the swinging end of the door 1, has mounted thereon a plate 20, which is countersunk therein and secured by means of the screws 21. This

plate is similar in design to the plate 3 on the door, and is provided with a socket 22 disposed within the frame and in alinement with the locking bolt 5 to form a keeper for the latter when the door is disposed to its closed position. It will therefore require a turning of the spindle 9 to release the locking bolt 5 from the keeper after the door has, once been disposed to its closed position. Secured on the inner and outer faces respectively of the door 1, are the plates 23 and 24, through which the spindle 9 extends, said plate 24 being provided with an integral tubular portion 25 on which the knob 26 is formed and that portion of said spindle which extends through the tubular portion 25 is reduced as shown at 28.

The reduced portion 28 of the spindle 9 has mounted thereon a washer 27 one face 20 of which abuts the shoulder formed between the main portion of the spindle and the said reduced portion thereof, the opposite face of said washer being reduced to form a shoulder which abuts the shoulder 27' 25 formed on the tubular portion 25 and a coil spring 29 is encircled about said reduced portion 28 between the opposite face of the washer 27 and a head 30 formed on the free end of the reduced portion 28. Thus it will 30 be seen that the tendency of the spring 29 will be to force the spindle outwardly toward the knob 26, it being appreciated that the shoulder formed by the reduced portion 28 and the main portion of the spindle 9 will limit said outward movement. This 35 knob 26, which is disposed on the outer face of the door 1, is substantially hollow, having mounted on the inner face of the outer wall thereof, a block or thickened plate 31, 40 said plate having one face thereof provided with a socket 32 to receive a projection 33 formed on the head 30 of the reduced portion of said spindle. This block or plate 31 is so disposed that the socket 32 therein will 45 be in normal alinement with the projection 33 so that when the spring 29 forces the spindle in the position shown in Fig. 4, the projection 33 will be received in the opening 32, which will be the normal position of 50 the device and the socket 32 communicates with a channel or additional socket 34 extending through the plate or block 31, the wall of said latter socket or channel being provided with inwardly or laterally disposed pins 35. The outer wall of the knob 55 26 is provided with an axial slot or the like 36 which communicates with the channel or socket 34 in the plate 31 and through which a key 37 may be disposed. This key must 60 obviously be provided with openings to register with the pins 35 in the wall of the socket 34 so that said key may be readily turned therein and is also provided on its outer end with lugs or the like 38 which are 65 adapted to engage openings in the projec-

tion 33 of the head 30. When the key 37 is so disposed through the knob 26, which is a substantial lock, so that the lugs on the free end of the same engage the openings in the projection 33, said key may be turned, which turning will cause the spindle 9 to be turned, thereby withdrawing the locking bolt 5.

It will be appreciated that in view of the fact that the knob 26 is formed directly on the plate 24 and not rotatable with respect thereto, said spindle 9 may not be turned until the proper key has been inserted and I have also provided means whereby the locking bolt may be withdrawn by operation from the inner side of the door, even though a slug or fake key has been inserted in the lock and broken therein, which means will be hereinafter and more particularly described.

The plate 23, which, as stated previously, is the plate secured to the inner face of the door 1, has formed thereon an integral collar or the like 39, through which extends the spindle 9 and the outer face of which is beveled, as shown at 40 and a knob 41 is also provided, the same having formed thereon an integral tubular portion 42. The one end of said tubular portion is also provided with a collar portion 43 adapted to abut against the collar 39 and the contacting face of said latter collar portion 43 is beveled coincident to the beveling of said collar 39. The spindle 9 extends through this tubular portion 42 and into the knob 41, said spindle being secured to said tubular portion so that upon the turning of the knob 41, it will be appreciated that the spindle 9 will be turned. It will be seen, however, that the collar 39 is stationarily mounted with respect to the collar 43, so that as said knob 41 is turned to correspondingly turn the spindle 9, the beveled contacting faces of said collars 39 and 43 will cause said spindle 9 to be partially withdrawn, the spring 29 yielding under this drawing 110 action. It will, of course, be appreciated that the withdrawing of the spindle 9 will not effect the turning thereof, but will withdraw the projection 33 of the head 30 from the socket 32 and thus should there have been 115 a slug or other imitation key inserted within the knob 26 and broken off therein, the device will not be affected so far as operation thereof from the inside is concerned. It will be seen therefore that the locking bolt 5 may be withdrawn at any time desired from the inside by the mere turning of the knob 41 while said bolt may only be withdrawn from the outside by the insertion of 120 the proper key through the knob 26 and the turning of said key.

From the foregoing it will be seen that I have provided a simple, inexpensive and efficient means for carrying out the objects of the invention and while I have particu- 130

larly described the elements best adapted to perform the functions set forth, it is obvious that various changes in form, proportion, and in the minor details of construction 5 may be resorted to without departing from the spirit or sacrificing any of the principles of the invention.

Having thus described this invention, what is claimed is:—

- 10 1. A device of the class described comprising a casing, a bolt slidably arranged therein, said bolt being provided with a pair of longitudinal alining slots, a spindle extending through said slots, means to normally dispose said bolt in its extended position, a pair of pivoted arms carried on the rear end of said bolt, and a trip member carried on the spindle adapted for engagement with the free ends of said arms to retract said bolt upon the turning of the spindle.
- 15 2. A device of the class described comprising a casing, a bolt slidably arranged therein, said bolt being provided with a pair of alining longitudinal slots and also provided with a central longitudinal channel, a spindle extending through said slots having mounted thereon an arcuate trip member, said trip member being provided 20 with a pair of shoulders on the periphery thereof, a spring member disposed in said longitudinal channel and engaging said trip member to normally dispose the bolt in its extended position, and a pair of arms pivotally carried on the rear end of said bolt and having the free ends thereof disposed in engagement with the shoulders on said trip member, whereby said bolt will be retracted 25 upon the turning of the spindle.
- 30 3: The combination with a door, and a
- 35 bolt slidably arranged thereon, of a spindle extending transversely through said door to coöperate with said bolt, a pair of knobs for the door, one of said knobs being carried directly on said spindle, the other of said knobs being mounted on the door proper, means in connection with the last referred to knob adapted to receive in engagement therewith a portion of said spindle, additional means coöperating with the last mentioned knob for turning said spindle, and means coacting with the first referred to knob for withdrawing said spindle from its operative connection with said other knob.
- 40 4. In a device of the class described, the combination with a door and a bolt slidably arranged therein, of a spindle extending through the door to coöperate with said bolt, said spindle being capable of a slight transverse movement therethrough, a pair 45 of knobs for the door, one of said knobs being carried directly on the spindle, the other knob being mounted on the door proper, a head formed on one end of said spindle and disposed within the last mentioned knob, means in connection with said last mentioned knob to receive a portion of said head when the spindle is in its normal position, means adapted for application to the last mentioned knob for engagement 50 with the head to turn said spindle, and means co-acting with the first mentioned knob for withdrawing said spindle from its operative connection with said other knob.
- 45 5. In testimony whereof I hereunto affix my 55 signature in the presence of two witnesses.
- DELLAMOIN L. HAMILTON.
